UNITED STATES PATENT OFFICE.

GERTRUDE V. D. SOUTHWORTH, OF SYRACUSE, NEW YORK.

BOOK-COVER.

961,548.

Specification of Letters Patent. Patented June 14, 1910.

Application filed January 16, 1909. Serial No. 472,586.

To all whom it may concern:

Be it known that I, GERTRUDE V. D. SOUTHWORTH, a citizen of the United States, residing at 314 Highland avenue, Syracuse, in the 5 county of Onondaga and State of New York, have invented new and useful Improvements in Book-Covers, of which the following is a specification.

My invention relates to book-covers used 10 for the protection of the binding of books which are subject to much use, such as the books of schools, public libraries, etc., and consists in a book-cover peculiarly formed and constructed so that it may be adjusted 15 and applied quickly, easily and accurately to the book. The cover of each particular size has a considerable range of adjustment so that it may be applied to books differing as to size, both in length, breadth and thickness. 20

The essential features of my peculiar cover is the one-piece blank of sufficiently heavy paper or other suitable material, having a substantially rectangular central body portion 25 provided with a substantially continuous flap along its upper edge, and flaps on the right and left edges and separate lower flaps on its lower edge, said lower flaps being respectively adjacent to the two ends; 30 the two lower flaps are turned in and up against the body and the left end flap is turned in and gummed to the left lower flap forming a pocket for the lower corner of the front cover of the book. Two converging 35 lines, or two series of converging lines, (the lines of each series being parallel) are printed adjacent to the top of the blank and on each side of the center. Horizontal lines parallel to the upper edge of the blank may 40 be printed between, or across, the converging lines.

My invention will be understood by reference to the drawing herewith, showing the inside of the book-cover, in which the reference letters and numerals of this description 45 are used to indicate the various parts.

In the drawing Figure A indicates the substantially rectangular body of the blank or cover having integral flaps as follows; 1 50 the left end flap; 2 and 3 the left and right lower flaps; 4 the right end flap; and a substantially continuous upper flap having its left, central, and right portions indicated 55 respectively by the numerals 5, 6, 7 which is cut to form separate flaps, as hereinafter described, when the cover is being applied to

the book. A central lower flap 8 is desirable, but not essential, to reinforce the center of the lower edge. Whether flap 8 is used or not, the space between flaps 2 and 3 is wide 60 to accommodate books of different widths and thicknesses.

At the upper edge of the cover, extending on each side of the center, is printed the two series of converging lines a, a', a^2, a^3 , etc., 65 and b, b', b^2, b^3 , etc. Only the outer lines a and b are essential but it is more convenient to print the series of parallel lines to guide the cuts in separating the central upper flap 6. The horizontal lines c, c' etc. are also 70 convenient but of less importance.

To complete the cover ready to be delivered to the users, flaps 1 and 2 are turned in as shown and pasted at 10, forming a pocket to receive the lower corner of the 75 front cover of the book; flap 3 is folded up to serve as a guide for the back cover of the book, in applying the cover to the book. Gum is also applied at 11, 12 and 13 as indicated. 80

To apply the cover to a book, first insert the lower corner of the front cover of the book in the pocket formed by flaps 1 and 2. Then mark the particular horizontal line c indicating the top of the book, and on said 85 line mark at both sides the converging lines which at that point are sufficiently spaced just to include the back of the book, where they cross the horizontal line as marked. In case the horizontal lines are not printed, the 90 same indication may be made merely by marking both the two correct converging lines exactly at the top of the book. Then cut along the two converging lines from the upper edge to the line, or marks, indicating 95 the top of the book, to separate flap 6 from flaps 5 and 7. Then fold in flap 6 (and flap 8 when used) to be outside of the back of the book; adjust flap 3 over the back cover of the book; fold down flap 5 snugly 100 over the top edge of the cover of the book and gum to flap 1 by moistening the gummed portion 11; fold down flap 7 over the top edge of the back cover of the book and finally fold in the flap 4 snugly to fit 105 against the vertical edge of the back cover of the book, and gum it to flaps 3 and 7 by the gummed portions 12 and 13.

My book-cover is economical to manufacture and simple and convenient to apply 110 to books, because it is strictly a one-piece book-cover, cut or stamped at one operation,

from suitable material such as rather heavy manila paper; by the initially made pocket the lower left bottom edge and the left hand edge are positively established, and by the 5 initially folded upright flap the entire lower edge is established, thus giving a true and positive bottom line, insuring an accurate fit; by means of the converging parallels the cutting of the central top flap is accurately 10 indicated and by the horizontal parallels, when used, the true line for folding in the top flap, according to the height of the book, is indicated. It will thus be seen that my 15 book-cover has a wide range of adjustability for books of various sizes and may be easily removed from books.

Having thus described my invention, what I claim is,—

1. As a new article of manufacture a 20 book-cover composed of a single piece of paper and having a central substantially rectangular body portion and integral flaps on the four edges of said body, said flaps being adapted to be folded inwardly, and 25 two converging series of lines inscribed on the upper portion of the inner surface of the cover, the lines of each series being parallel and the two series being arranged respectively on each side of the center.
2. In a one-piece book-cover, the combination with a substantially rectangular body portion, of left and right flaps on the lower edge of the body, said flaps being turned up in alignment against the inner surface 30 of the body, a left edge flap extending substantially from end to end of the left edge of the body, said edge flap being turned in and gummed by its lower end to the outer surface of the left lower flap, forming a 35 pocket for the front cover of the book to be covered, a single, continuous upper flap extending substantially from end to end of

the upper edge of the body, a right flap extending substantially from end to end of the right edge of the body, two converging 45 series of parallel lines printed on the upper portion of the inner surface of the book-cover said series being arranged one on each side of the center of the book-cover and a third series of parallel lines printed across the 50 converging lines below the upper edge of the book-cover and parallel to said upper edge.

3. As a new article of manufacture, a 55 book-cover composed of a single piece of paper and having in combination a substantially rectangular central body, separate lower flaps on its lower edge, arranged one toward each side and having a space between their adjacent ends, said flaps being 60 turned upwardly against the inner surface of the cover, a left flap on the left edge turned in and having its lower end lying over and gummed to the left end of the lower left flap, a continuous upper flap on 65 the upper edge of the body and a right flap on the right edge of the body, gum for moistening on the inner surface of the left end portion of the upper flap and on the upper and lower portions of the right flap, two 70 converging series of parallel lines printed on the inner surface of the cover, said series being arranged one on each side of the center and a series of parallel horizontal lines printed across the lower portion of the 75 series of converging lines.

In testimony whereof I have signed my name to this specification in the presence of two subscribing witnesses.

GERTRUDE V. D. SOUTHWORTH.
